UNITED STATES PATENT OFFICE

145,222

DESIGN FOR A REFRIGERATOR

Raymond Loewy, New York, N. Y., assignor to The Coca-Cola Company, Wilmington, Del., a corporation of Delaware

Application December 21, 1945, Serial No. 124,919

Term of patent 14 years

(Cl. D67—3)

To all whom it may concern:

Be it known that I, Raymond Loewy, a citizen of the United States and resident of New York, New York County, New York, have invented a new, original, and ornamental Design for a Refrigerator, of which the following is a specification, reference being had to the accompanying drawing, forming part thereof.

Fig. 1 is a view in perspective showing the front, top and one side of a refrigerator, embodying my new design; and

Fig. 2 is also a view in perspective showing the rear, top and other side thereof.

I claim:

The ornamental design for a refrigerator, as shown.

RAYMOND LOEWY.
